REFUSE HOLDER

John C. Brighton, Columbus, Ind., assignor to Arvin
Industries, Inc., Columbus, Ind., a corporation of Indiana

Filed Oct. 8, 1962, Ser. No. 72,016

Term of patent 14 years

(Cl. D14—3)

Fig. 1.

Fig. 2.

Fig. 3.

FIG. 1 is a perspective view of a refuse holder embodying my new design;

FIG. 2 is a rear elevation thereof;

FIG. 3 is a plan view thereof, but with the lid in open position;

FIG. 4 is a perspective view thereof with the wheels, axle, and handle grips omitted;

FIG. 5 is a rear elevation of the refuse holder shown in FIG. 4; and

FIG. 6 is a plan view of the refuse holder shown in FIG. 4, but with the lid in open position.

The dominant features of my design are shown in full lines.

I claim:

The ornamental design for a refuse holder, as shown and described.
